UNITED STATES PATENT OFFICE.

SAMUEL SELDEN AND OREN R. HANCHETT, OF ERIE, PA., ASSIGNOR TO
SELDEN & GRISWOLD MANUFACTURING COMPANY, OF SAME PLACE.

IMPROVEMENT IN PUMP-BRACKETS.

Specification forming part of Letters Patent No. 142,286, dated August 26, 1873; application filed
July 24, 1873.

To all whom it may concern:

Be it known that we, SAM'L. SELDEN and OREN R. HANCHETT, of Erie, county of Erie, State of Pennsylvania, have invented a new and useful Improvement in Pump-Brackets, of which the following is a full, clear, and exact description, reference being had to the accompanying drawings making part of this specification, in which—

Figure 1 is a rear view of the bracket, showing the pivot-block, to which the handle is secured, with the bracket broken away in front of one of the pivots or pivot-bearings. Fig. 2 is a perspective view of the pivot-block; and Fig. 3 is a perspective view of a pump, showing the bracket applied.

Similar letters of reference denote corresponding parts in all the figures.

The invention relates to a novel construction of the pump-bracket and pivot or pivot-block, for preventing endwise displacement of the pivot when in use; and consists in casting or otherwise constructing the pivot or pivot-block in the desired form, and then casting the U-shaped bracket thereon, in such manner as to cause the metal of the bracket to inclose or cover the ends of the pivot; or, if preferred, the pivot and bracket may be made in one piece, and the pump-handle connected with the fixed pivot by a loop-bracket adapted to turn freely on the pivot, this construction in either case serving effectually to prevent endwise displacement, and consequent loss of the pivot after the same has been once applied to the pump.

In the accompanying drawing, A represents the pivot-block; a, the pivot formed thereon, said block and pivot being made in any suitable or desired form, the former for convenience of attachment to the pump-handle or lever, and the latter, by preference, rounded at the ends, as shown, or made conical, as giving the best or most approved form of pivot, and the

whole either cast or wrought of iron or steel, as may be preferred.

When cast, and with the sand yet adhering to it, the said block may be placed in a mold formed for it by a print attached to the U-shaped bracket B, both being molded at the same time. When the bracket is cast, the metal closes around the pivot a, but does not adhere to it in consequence of being coated with sand. The sand will readily work out by a slight movement of the block, leaving it free for any required movement.

A wrought-iron or steel pivot may be applied in the same manner, and will thus be inseparably connected with the bracket, while at the same time adapted to turn freely in its bearings therein to accommodate the movement of the handle or lever C.

If preferred, the pivot may be formed or cast in one piece with the U-shaped bracket B, either extending entirely across from one arm to the other, or forming conical or cylindrical projections or teats from each arm; in which case the bracket should be cast first, and the plate cast to it, reversing the arrangement above described.

The plate or pivot-block will be connected with the handle in any usual or preferred manner.

Having now described our invention, what we claim as new, and desire to secure by Letters Patent, is—

The pivot a, in combination with the U-shaped bracket B, cast or otherwise formed upon or in one piece with the pivot or pivot-block, substantially as and for the purpose described.

In testimony whereof we have hereunto set our hands this 18th day of July, A.D. 1873.

SAM. SELDEN.
